UNITED STATES PATENT OFFICE.

HAROLD A. WEBSTER, OF HAVERHILL, MASSACHUSETTS, ASSIGNOR TO WEBSTER SHOE MACHINE COMPANY, OF HAVERHILL, MASSACHUSETTS, A CORPORATION OF MAINE.

SOLE-LEVELING MACHINE.

SPECIFICATION forming part of Letters Patent No. 729,820, dated June 2, 1903.

Application filed November 6, 1902. Serial No. 130,247. (No model.)

To all whom it may concern:

Be it known that I, HAROLD A. WEBSTER, of Haverhill, in the county of Essex and State of Massachusetts, have invented certain new and useful Improvements in Sole-Leveling Machines, of which the following is a specification.

This invention relates to sole-leveling machines in which a leveling-tool is caused to act upon the bottom of a sole supported and presented to it by a suitable jack, the tool and jack having such relative movements as will cause the tool to act effectively in leveling the sole. In another application for Letters Patent of the United States, filed by me August 13, 1902, Serial No. 119,514, I have shown a sole-leveling machine of this class in which the leveling-tool is a rotary tool having a ribbed perimeter longitudinally curved to conform to the transverse curvature to be imparted to the bottom of a sole, the ribs of the tool being composed of independent rolls. In said application the tool is represented as receiving a continuous rotation in one direction during the operation.

The present invention consists, mainly, in the provision of means for rocking or oscillating the tool instead of rotating it continuously, thereby giving the ribbed perimeter of the tool a back-and-forth motion upon the sole. This motion besides improving the quality of the work enables the acting surface of the tool to be divided up into sections, each having a different longitudinal curvature from the other or others, so that the tool can be adjustably mounted upon its supporting-shaft and turned from time to time to bring any desired section into operative position, the curvature of one section being, for example, that suited for the fore part of the sole, while the curvature of another section is suited for the shank part. The invention will now be described, and specifically pointed out in the claims.

Of the accompanying drawings, forming a part of this specification, Figure 1 represents a side elevation of a sole-leveling machine embodying my invention. Fig. 2 represents an end elevation of the leveling-tool and a part of the connecting-rod which gives it a

rocking motion, the shaft on which the tool is mounted being shown in section. Fig. 3 represents a section on line 3 3 of Figs. 1 and 2. Fig. 4 represents a longitudinal section of the leveling-tool, and Fig. 5 represents a transverse section of the same.

The same reference characters indicate the same parts in all the figures.

The frame of the machine as a whole is represented by *a*, while the jack as a whole is represented by *b*. The leveling-tool as a whole is represented by *c*. The said parts and the mechanism that operates the jack and leveling-tool are, as here shown, substantially the same as in the above-mentioned application, excepting that the leveling-tool instead of being continuously rotated, as shown in said application, is rocked or oscillated to give the acting portion of its periphery a back-and-forth or pendulous motion. The leveling-tool has a longitudinally-curved and ribbed perimeter, adapted to impart to a sole on the jack the usual transverse curvature, the said perimeter being composed of a plurality of rolls 2 3, adapted to rotate loosely, the rolls being preferably formed and arranged substantially as shown in the above-mentioned application. The heads 4 and 5, in which the rolls 2 and 3 are journaled, are formed on or affixed to a sleeve or tubular hub 7, through which passes the operating-shaft 8, which imparts motion to the tool. The sleeve 7 is adapted to be locked to the shaft 8 in different positions, so that any desired section or longitudinal strip of its perimeter may be caused to act on the sole, the locking means being hereinafter described.

The means for rocking or oscillating the tool are preferably as follows: *9* represents a connecting-rod, one end of which is pivoted at 10 to a crank-arm 12 on a shaft 13, driven by the power of the machine. The other end of the connecting-rod is pivoted at 14 to an arm or ear 15, affixed to the shaft 8 by means of a key or spline 16, said arm 15 having a hub 17 surrounding the shaft 8. The rotation of the shaft 13 therefore imparts, through the rod 9, a rocking motion to the shaft 8 and to the leveling-tool affixed thereto.

The means for locking the leveling-tool to

the shaft, as here shown, are as follows: 18 represents a flange formed on or rigidly affixed to one end of the leveling-tool and provided with a plurality of orifices 19, the number of orifices corresponding to the number of positions in which it is desired to lock the leveling-tool to the shaft. The arm 15 is provided with a spring-pressed bolt 20, adapted to engage either of the orifices 19, said bolt 10 having a retracting knob or handle 21. It will be seen that by withdrawing the bolt 20 and giving the leveling-tool a partial rotation a different portion of its perimeter may be brought into position for action, the said 15 portion being retained in acting position by engaging the bolt 20 with another orifice 19.

The perimeter of the leveling-tool is divided into longitudinal sections, each having a different longitudinal curvature from the 20 other or others, there being as many sections as there are locking-orifices 19. The different sections may be conveniently formed by making the rolls 2 and 3 at one side of the tool of a different curvature from the rolls at 25 the opposite side, as represented in Fig. 4, where the rolls at the lower side of the tool are shown as having a lesser curvature than the rolls at the upper side.

It will be seen that by imparting to the leveling-tool a rocking motion its ribbed perimeter is caused to move back and forth or reciprocate while in contact with the sole, this motion being found to give an improved result. It will also be seen that the rocking 35 motion permits the different sections of the tool to be made with different curvatures, thus enabling the operator to readily change the contour of the tool when shifting from the fore part to the shank, and vice versa, 40 also enabling the same tool to act on soles of different sizes or degrees of curvature.

I do not limit myself to the details of mechanism here shown for operating or for adjusting the tool, as these may be variously modified without departing from the spirit of my 45 invention.

I am aware that a leveling-roll journaled loosely in a frame which is mounted to oscillate on a center outside of and parallel with 50 the axis of the roll is not new. My improved leveling-tool differs from the roll above referred to in that its acting face is substantially concentric with the axis of movement

or oscillation of the tool, so that the tool has no lateral oscillating movement, and therefore has not the tendency to hammer and displace the work, which would exist if it were mounted to oscillate on a center outside of its axis of rotation. The concentric arrangement of the acting face relatively to the axis or center of oscillation makes the action of the tool very effective without hammering or displacing the work and gives results which in some respects are more desirable than when the tool is continuously rotated on an axis 65 concentric with its acting face.

I claim—

1. A sole-leveling machine comprising a leveling-tool, and means for oscillating said tool to give its acting face a back-and-forth motion, the said acting face being substantially concentric with the axis or center of motion of the tool.

2. A sole-leveling machine comprising a leveling-tool having a ribbed acting face, and means for oscillating said tool, the said acting face being substantially concentric with the axis or center of motion of the tool.

3. A sole-leveling machine comprising a leveling-tool having a plurality of ribbed acting faces of different curvatures, said tool being rotatably mounted to bring either face into operative position, and means for oscillating the tool.

4. A leveling-tool having a plurality of 85 ribbed sections longitudinally curved, and surrounding an axis or center of motion, said sections having different longitudinal curvatures.

5. In a sole-leveling machine, the combination of the following elements, viz., first, a leveling-tool comprising heads and rolls journaled in said heads and collectively forming longitudinally-curved ribbed sections of varying curvature; secondly, a shaft on which the said tool is adjustably mounted, the shaft and tool having complementary locking means to secure the tool to the shaft in different positions; and thirdly, means for oscillating the shaft and tool.

In testimony whereof I have affixed my signature in presence of two witnesses.

HAROLD A. WEBSTER.
